WATER-COOLED GRATE

Leslie M. Barden, Downers Grove, Ill., assignor to
Joseph J. Heritage, Chicago, Ill.

Application July 31, 1940, Serial No. 348,803

12 Claims. (Cl. 122—374)

There are a number of fuels having a low relative cost or having other advantages, such as a high heat content and a low ash content, which are burned with difficulty on ordinary grates in hand fired furnaces. Some of these fuels, such as petroleum coke, tend to form a solid bed or slag or clinkers when an attempt is made to achieve high rate of combustion. Difficulty is also encountered with petroleum coke and with coals of high sulphur content with burning out of the ordinary grate bars because of the corrosive nature of the ash or clinker formed and because of the high temperature to which the grate bars are heated.

It has been found that these difficulties can be obviated by the use of water cooled grate bars which retard or reduce the formation of clinkers and which remain relatively cool and therefore not subject to high temperature corrosion.

Many forms of water cooled grates have been proposed, but few, if any, of these have come into commercial use, probably because they involve considerable complications in the way of piping and were difficult to install.

The principal object of this invention is to provide a water cooled grate which is extremely simple in construction and involves a minimum amount of material, and which can be installed in a boiler with the minimum amount of work.

Another object of this invention is to provide a water-cooled grate whose design is as simple as possible and which nevertheless has a good circulation through it.

Another object of this invention is to provide a simple water cooled grate which will improve both the heating capacity and the efficiency of the boiler in which it is installed.

One of the principal features of this invention consists in making the grate of steel or wrought iron tubing welded together and in two separate portions which may be easily inserted into the furnace either through the fire doors or through the ash pit doors.

Another feature of this invention is the provision of short angular connecting tubes between the headers of the water-cooled grate and the water legs of a boiler and arranging the connecting tubes in a particular manner to insure good circulation of water through the grate.

Another feature of this invention when used in connection with a horizontal return tubular boiler is the provision of risers within the fire box forming direct connections between the headers of the water-cooled grate and the boiler, the headers being arranged in a manner which

will insure good circulation of water through the grate.

Other objects and features of the invention will appear from the following description and claims and the accompanying drawings in which:

Figure 1 is a side view of one of the preferred forms of the invention installed in the combustion chamber of a stationary locomotive type boiler, the boiler and setting being broken away to more clearly show the invention;

Figure 2 is a section on the line II—II of Figure 1, looking in the direction of the arrows;

Figure 3 is a plan view of the grate shown in Figure 1;

Figure 4 is a section on the line IV—IV of Figure 3, looking in the direction of the arrows;

Figure 5 is a side view of another of the preferred forms of the invention as used in connection with a horizontal return tubular boiler, the boiler setting being shown in section in order to more clearly show the invention;

Figure 6 is a sectional view through the furnace of a boiler of the type shown in Figure 1, showing a modified form of the invention; and

Figure 7 is a view similar to Figure 6 and showing another modification of the invention.

The particular form of the invention shown in Figures 1 to 4 of the drawings is shown installed in a conventional stationary locomotive type boiler 10 of moderate size, such as is commonly used for heating purposes. The boiler 10 is placed in a brick setting 11 which provides the ash pit 12, in the conventional manner. Access to the furnace 13 of the boiler 10 is provided through doors 14 and 15 on the front of the boiler, and access to the ash pit 12 is provided through a door 16 located below the front of the boiler.

The grate 17 is formed almost entirely of steel tubing welded together as shown in Figures 3 and 4, and is made in two separate halves. Each half comprises a front header 18 and a rear header 19 joined by a plurality of straight tubes 20 which form the part of the grate upon which the fire rests. Each section of the grate 17 is provided with lugs 21 welded to the grate tube at the inner end of the grate section and provided with apertures for receiving bolts 22 by means of which the two sections of the grate are bolted together.

Each of the front headers 18 is provided with a tubular elbow 23 welded to it and extending upwardly and rearwardly and then laterally outwardly. Each of the rear headers 19 is provided

with two tubular elbows 24 and 25 welded to it and extending upwardly and forwardly and then laterally outwardly. One rear elbow 24 extends from the rear header 19 near its outer end, and the other rear elbow 25 extends from the rear header 19 near its inner end, as shown in Figure 3.

The two front headers 18 are provided with blow-off connections 26 and 27 on their under side, the two connections 26 and 27 being connected together by tubes 28 and 29 and a flange coupling 30.

One blow-off connection 26 is arranged to receive a blow off-pipe 31 which leads to a valve 32 located above or at one side of the ash pit door 16.

Since the grate 17 is made of two separate sections, each of these sections, comprising the front and rear headers 18 and 19, the grate tubes 20, the front and rear circulation elbows 23, 24, and 25, and the blow off connections 26 and 28 or 27 and 29, can be entirely assembled and welded together outside of the boiler. The two sections can then be inserted into the furnace 13, either by way of the ash pit door 16 and the ash pit 12 or by way of the furnace door 15. If necessary, the furnace doors 14 and 15 and the door frame 33 may be removed to facilitate the insertion of the portions of the grate into the furnace 13.

The grate sections are placed upon brackets 34 and 35 at the front and rear of the furnace, each of the headers 18 and 19 resting upon the brackets at one end of the furnace, as shown in Figure 1. The location of the ends of the circulation elbows 23, 24, and 25 on the side walls 36 of the furnace is now marked, the grates 17 are lifted up and lowered into the ash pit 12, and holes are cut by means of an oxy-acetylene torch or other suitable means in the furnace walls 36 at the places marked. After the holes in the furnace walls 36 have been cut, the grates 17 are replaced in position on the brackets 34 and 35, the two sections are bolted together, and the ends of the elbows 23, 24 and 25 are welded to the furnace walls, thereby connecting the passages within the grates to the water legs of the furnace. The installation is completed by putting in and connecting the blow off pipe 31 and blow off cock 32.

It will be noted that both the front and rear headers 18 and 19 are larger than the grate tubes 20 and that the rear header 19 is substantially larger than the front header 18. In one installation which has proven to be eminently satisfactory, the grate tubes are two inches in diameter, the front header is three inches in diameter, and the rear header is four inches in diameter. It will also be noted that the grate tubes 20 slope slightly upward towards the rear of the furnace, and that two circulation elbows 24 and 25 are provided on each rear header 19, whereas only one circulation elbow 23 is provided on the front header 18. These apparently minor details are of great importance as they are believed to be the reason for the practical and successful operation of the device.

Although the circulation elbows 23, 24 and 25 extend upwardly at both the front and rear, good circulation through the grates is secured because of the slight incline of the grate tubes 20 and because of the fact that the rear circulation elbows 24 and 25 are more in the path of the flames and hot products of combustion rising from the fire bed on the grate tubes 20

to the boiler tubes 37 opening into the back of the furnace 13. These factors, coupled with the fact that there is less resistance to circulation from the boiler tubes through the large rear header 19 and the two rear connection elbows 24 and 25 than through the small front header 18 and the single front connection elbow 23 insures that the heated water and the steam generated in the grate tubes 20 will flow towards the rear of the boiler and into the water legs through the rear header 19 and the rear connection elbows 24 and 25.

In Figure 6, I have illustrated a modified form of the invention shown in Figure 1. In this modified form of the invention, the grates 40 are formed in two sections and are generally similar to the grates 17 in the first form of the invention. They comprise tubular grate bars 41 extending between front and rear headers 20 42 and 43 which rest upon brackets 34 and 35 at the front and rear of the furnace 43. Each of the two front headers 42 is provided with a connecting elbow 44, similar to the connecting elbow 23 in the first form of the invention, which extends upwardly and rearwardly and then laterally outwardly and is welded into the side wall 36 of the furnace.

Each of the two rear headers 43 is provided with two connecting elbows 45 and 46, but these, instead of being connected to the side wall 36 of the furnace, rise vertically and then turn back into the tube sheet 47 at the rear of the furnace, the connection to the tube sheet 47 being made by welding. It will be noted that, as in the first form of the invention, there are two rear connection elbows 45 and 46 and one front connection elbow 44 for each section of the grate and that the rear connection elbows 45 and 46 extend up higher and are more in the path of the flames than the front connection elbow 44. Because of this and because of the fact that the rear header 43 is slightly higher than the front header 42, the circulation of water through the grate will be maintained in the same manner as in the first form of the invention.

Another modification of the form of the invention illustrated in Figures 1 to 4 is shown in Figure 7. In this modification, the grate 50 is made in two sections as before and comprises grate tubes 51 extending between front and rear headers 52 and 53 which are supported upon brackets 34 and 35 at the front and rear of the furnace. Each of the two front headers 52 is provided with a single connecting elbow 54 similar to the connecting elbow 44 in the previously described form of the invention.

Each of the two rear headers 53, instead of being provided with connecting elbows, is provided with a pair of risers 55 and 56 whose upper ends are welded into the crown sheet 57 of the boiler. One riser 56, which is connected to the header 53 near the side of the furnace, is fastened into the crown sheet 57 near the side of the furnace, and the other riser 55, which is connected to the header 53 near the center of the furnace is fastened into the crown sheet 57 near its center.

The construction shown in Figure 7 is especially suitable for use in boilers in which the fire tubes 37 are arranged in groups with vertically extending spaces between them for the downward circulation of the water in the boiler. In such a boiler, it is practical to arrange the risers 55 and 56 in front of those portions of the tube sheet 47 through which no fire tubes 37 extend,

thus providing an arrangement which does not interfere with the cleaning of the fire tubes 37 and which nevertheless allows the risers 55 and 56 to extend up to the crown sheet 57. In this form of the invention, exceptionally good circulation is provided because of the relatively great height of the risers 55 and 56 and their position directly in front of the tube sheet 47. In the installation of this form of the invention, the risers 55 and 56 are welded to the headers 53 after the grates 50 have been permanently placed in position, since the length of the risers makes it impractical to introduce the grates into the furnace with the risers attached.

A form of the invention which is particularly adapted for use with horizontal return tubular boilers is illustrated in Figure 5. In this construction, the cylindrical boiler 60 is supported by hangers 61 from beams 62 carried by uprights 63. The boiler is provided with a setting or casing 64 which may be of steel or masonry or both and which contains a furnace 65 located below the boiler 60 and formed of suitable refractory material. Access to the furnace 65 is provided through fire doors 66, and access to the ash pit 67 below the furnace is provided through ash pit doors 68 in the conventional manner.

The grate 70 is formed in two sections, as in the previously described forms of the invention, and each of the sections comprises front and rear headers 71 and 72 joined by a plurality of grate tubes 73 and connected to the bottom or "belly" of the boiler 60 by risers 74 and 75.

There is one riser 74 for each of the two front headers 71, these risers being placed at the outer ends of the headers 71 and extending up near the side wall of the furnace so as not to interfere with the stoking of the furnace. The upper ends of the risers 74 are welded into the bottom of the boiler 60 but do not project within the boiler.

The risers 75 connecting the rear headers 72 to the boiler 60 are arranged one near each end of each of the rear headers 72 so that there are a total of four such risers 75. Each of the risers 75 extend through the shell 76 of the boiler and project up within the boiler as far as may be practical. In general, the height to which the risers 72 can project within the boiler is limited by the fire tubes 77 characteristic of this type of boiler, but this distance should be made as great as possible without obstructing the end of the riser 75 or placing it above the water line of the boiler.

In installing this form of the invention, two halves of the grate are fabricated as in the other forms of the invention, but the risers 74 and 75 are not secured to the main portion of the grates until the grate is set in place in the furnace. The risers 74 and 75 are then located in their proper place and welded into position.

It will be noted that, in the form of the invention shown in Figure 5, the rear header 72 is slightly higher than the front header 71, as in the other forms of the invention, and that the upper ends of the rear risers 75 are at least as high as the upper ends of the front headers 74, even though the front headers 74 enter the boiler to one side of the center at a point above the lowest point of the boiler while the rear risers 75 extending up from the inner ends of the rear headers 72 enter the boiler at its lowest point. It will also be noted that the rear risers 75 lie directly in the path of the flames and products of combustion from the fire bed resting upon the

grate bar 73 to the rear end of the boiler and that they will therefore receive much more heat than the front risers 74. These facts insure a good circulation of water through the grate and prevent any portion of it from overheating while at the same time greatly increasing the heat absorbing capacity of the boiler unit.

From the above it will be seen that I have provided water-cooled grates which are extremely simple and which are nevertheless arranged to provide positive circulation of the water therein. It will also be seen that I have provided water-cooled grates which can be installed in internally fired boilers, return tubular boilers and other forms of boilers with the minimum amount of piping or other complications, and that the grate itself is so simple and comprises so few parts as to allow it to be economically manufactured for individual boilers.

While I have shown only four of the preferred forms of my invention, it will, of course, be understood that many variations, such as would occur to the skilled mechanic, for example, may be made without departing from the spirit of the invention. For example, the form of the invention shown in Figure 5 may be employed with other forms of boilers similar to the horizontal return tubular boiler, such as, for example, the "Herbert" detachable fire box boiler which differs from the ordinary horizontal return tubular boiler in that it is provided with a number of horizontal water tubes, at each side of the furnace, these tubes extending between upright headers connected to the main boiler drum. I therefore claim all constructions falling within the terms of the following claims.

I claim as my invention:

1. A boiler installation comprising a furnace, a boiler forming at least one wall of said furnace, front and rear headers at the bottom of said furnace, said rear header being at a higher level than said front header, tubular grate bars extending between said headers, means in said furnace for confining the flames and the products of combustion in a predetermined path from a fire resting on said grate bars, means extending up from and connecting said front header to said boiler, and connections extending up from said rear header into said flame and combustion path and connected to the portion of said boiler forming a wall of said furnace.

2. In combination, a boiler having a furnace at least partly surrounded by water spaces, a grate at the bottom of said furnace, said grate comprising tubular bars extending between headers, means in said furnace for confining the flames and the products of combustion in a predetermined path from a fire resting on said grate, and elbows rising from said headers and connected directly to at least one of said water spaces, the elbows connected to one of said headers extending into said flame and combustion path.

3. In combination, a boiler having water spaces at the sides of a furnace, and a grate at the bottom of said furnace, said grate comprising tubular bars extending between front and rear headers, one of said headers being slightly higher than the other of said headers, means in said furnace for confining the flames and the products of combustion in a predetermined path from a fire resting on said grate, and elbows rising from said headers and connected directly to at least one of said water spaces, said elbows rising from the upper of said headers into said flame and combustion path, there being at least one more elbow

rising from the upper one of said headers than from the lower one of said headers.

4. In combination, a boiler having a furnace at least partly surrounded by water spaces, a header at the bottom front of said furnace, a second header at the bottom rear of said furnace and slightly higher than said first header, tubes forming grate bars extending between said headers, fire tubes in said furnace so positioned to receive the flames and products of combustion as to control their path of movement from a fire resting on said grate bars, means connecting said front header to one of said water spaces, and elbows rising into said flame and combustion path from said rear header into said furnace and connected directly to one of said water spaces.

5. In combination, a boiler having water legs, said legs defining a furnace, a header at the bottom front of said furnace, a second header at the bottom rear of said furnace and slightly higher than said first header, tubes forming grate bars extending between said headers, fire tubes in said furnace so positioned to receive the flames and products of combustion as to control their path of movement from a fire resting on said grate bars, means connecting said front header to one of said water legs, and elbows rising into said flame and combustion path from said rear header into said furnace and connected directly to one of said water legs, said elbows forming the sole connection between said rear headers and said boiler.

6. In combination, a boiler containing a furnace and fire tubes extending from the back of said furnace, a header within said furnace at the bottom front thereof, a second header within said furnace at the bottom rear thereof and slightly higher than said first header, tubes forming grate bars extending between said headers, means connecting said first header to said boiler, and elbows rising upwardly and forwardly from said rear header and connected to the side walls of said furnace, said elbows being located in the path of flame and products of combustion from a fire resting on said grate tubes to said fire tubes.

7. A water cooled grate for use with boilers having internal furnaces, comprising front and rear headers, straight tubes extending between and welded to said headers and forming grate bars, and connecting elbows welded to said headers and lying in planes passing through said headers and converging upwardly, the ends of said elbows extending slightly beyond the ends of said headers and being adapted to be welded to the side walls of said furnace.

8. A water cooled grate for use with boilers having internal furnaces, comprising front and rear headers, said rear header being larger than said front header, straight tubes extending between and welded to said headers and forming grate bars, and connecting elbows welded to said

headers and lying in planes passing through said headers and converging upwardly, the number of connecting elbows welded to said rear headers being larger than the number thereof welded to said front header, and the ends of said elbows extending slightly beyond the ends of said headers and being adapted to be welded to the side wall of said furnace.

9. In combination, a boiler containing a furnace having a sheet wall at the back thereof, fire tubes opening into the upper portion of said sheet wall, a rear header in front of and at the bottom of said sheet wall, a front header at the front of said furnace and slightly lower than said rear header, tubes forming grate bars extending between said headers, means connecting said front header to said boiler, and tubular members extending up into said furnace from said rear header and connecting the rear header to said sheet wall adjacent said fire tubes.

10. In a hot-water heating system having a furnace with a fire-box and a boiler, a portion of said boiler forming a wall closure for said fire-box, and a grate at the bottom of said fire-box, said grate being formed of connected hollow members including a header at the front end of said fire-box, a header at the rear end of said fire-box at a level above the front header, grate members extending between said headers, and risers extending upwardly from said headers into flow communication with said boiler, the risers from one of said headers projecting into the path of flames and combustion products flowing from a fire resting on said grate members.

11. In a hot-water heating system having a furnace with a fire-box and a boiler, a portion of said boiler forming a wall closure for said fire-box, a grate formed in a plurality of sections, means removably connecting said sections together, each grate section having a hollow header at the front end of said fire-box, another hollow header larger than said front header at the rear of said fire-box, said rear header being positioned above said front header, hollow sloping grate members extending between said headers, and connections inside of said fire-box between said headers and the boiler wall closure for said fire-box.

12. In combination, a boiler containing a furnace having an outlet at the rear end thereof, a header within said furnace at the bottom front thereof, a second header within said furnace at the bottom rear thereof, hollow grate bars extending between said headers, means connecting said first header to the boiler, and hollow members rising upwardly and forwardly from said rear header and connected to the side walls of said furnace, said hollow members being located in the path of flames and products of combustion flowing from a fire resting on said grate bars to said furnace outlet.

LESLIE M. BARDEN.
